CLAIM

The ornamental design for a flower vase, as shown and described.

DESCRIPTION

FIG. 1 is a perspective view of a flower vase showing our new design;

FIG. 2 is an enlarged perspective view of the detail 2 shown in FIG. 1 thereof; and,

FIG. 3 is a front elevational view thereof.

The broken lines are included to show portions of the flower vase that form no part of the claimed design.

The claimed design is shown in solid lines in the drawings but the surface behind the features shown in solid lines is unclaimed.
